STEAM GENERATING SYSTEM FOR
VEHICLES

Roland Williams, San Francisco, Calif.

Application January 16, 1951, Serial No. 206,130

3 Claims. (Cl. 122—41)

1

This invention relates to steam generating systems, and more particularly to a steam generating system for a steam turbine.

A main object of this invention is to provide a novel and improved steam generating system for use with a steam turbine, said system involving relatively simple components, being reliable in operation, and providing efficient and economical conversion of water into high pressure steam for use in driving the turbine.

A further object of the invention is to provide an improved steam generating system for a steam turbine particularly adapted for use on vehicles, said system providing extremely rapid and economical conversion of water into steam, providing a saving in fuel as over previous steam conversion systems, being simple to operate, being easy to start, and providing a wide range of available steam power, whereby the system has exceptional flexibility which makes it especially suitable for use on vehicles.

Further objects and advantages of the invention will become apparent from the following description and claims, and from the accompanying drawing, wherein the single figure diagrammatically illustrates an improved steam generating system constructed in accordance with the present invention.

Referring to the drawings, 11 designates a steam turbine which is generally conventional in construction and which includes the drive shaft 12 on which is mounted the turbine rotor having the blades 13. The shaft 12 is journaled in a housing 14. Secured to one end of the shaft is the gear 15 and secured to the opposite end portion of said shaft is the gear 16. Designated at 17 is a larger gear journaled in a housing portion 18, the larger gear 17 meshing with the gear 16, as shown. Designated at 19 is a water pump having the helical impeller 20 mounted on the shaft of gear 17, said impeller being mounted in the cylindrical housing 21 of the pump 19. Designated at 22 is a water reservoir which is connected by a conduit 23 through a manual valve 24 to the intake port of the pump 19. Designated at 25 is a vaporizer which is mounted in axial alignment with the shaft 26 of gear 17, the end of shaft 26 extending into the right end of the vaporizer 25, as viewed in the drawing, and having mounted thereon the fan 27. The vaporizer is provided adjacent the fan 27 with the air intake conduit 28.

As shown in the drawing, the vaporizer is formed at its right end with the conical com-

2

bustion chamber portion 29 which converges toward a convex wall portion 30 secured transversely in the vaporizer, said wall portion 30 dividing the chamber into two sections, the section at the right of the wall 30, as viewed in the figure, being a fuel combustion chamber, and the portion at the left of the wall 30 being the steam generating space or vaporization chamber of the vaporizer. Designated at 31 is a liquid fuel tank which is connected by a conduit 32 to a rotary pump 33 driven by the shaft 26 and located adjacent the end of the fuel combustion section 29. The outlet of the pump 33 is connected by a conduit 34 to a fuel injection nozzle 35 located in the conical combustion space 29. Designated at 36 is an ignition plug mounted in the combustion chamber portion opposite the nozzle 35. The high voltage electrode of the spark plug 36 is connected by a conductor 37 to the high voltage terminal 38 of a conventional ignition coil 39. The energizing winding of the ignition coil 39 is connected by a wire 40 to a control switch 41 provided on a control panel 42. Wire 40 is connected through switch 41 to a conductor 43 which is in turn connected through a voltage regulator 44 and a conductor 45 to the ungrounded terminal 46 of a storage battery 47. The grounded terminal of battery 47 is at 48.

Conduit 32 is provided with an electrically operated valve 49 which is connected to the battery 47 by an energizing circuit, not shown, which includes a thermostatic switch 50 mounted in the portion of the vaporizer 25 located to the left of the wall element 30, as viewed in the figure. For example, the switch 50 may be included in the ground return connection 51 of the energizing circuit of the valve. The fuel supply conduit 32 also includes a manual valve 52 located between the thermostatically controlled valve 49 and the fuel tank 31.

As shown in the figure, the vaporizer 25 is provided at the right side of the wall element 30 with an exhaust conduit 53 which provides exhaust of the gaseous products of combustion resulting from the ignition of the liquid fuel supplied by nozzle 35.

The outlet of pump 19 is connected by a conduit 54 to a water injection nozzle 55 mounted axially in the left side portion of the vaporizer 25 and directed toward the concave side of the wall element 30. Mounted in the left portion of the vaporizer 25 is a conical, centrally apertured baffle wall 56 which surrounds the nozzle 55, the central opening of the baffle wall 56 being

located to the right of the orifice of the nozzle 55, as viewed in the figure, and said conical baffle wall 56 being provided with reversely directed steam escape ports 57 which provide passage of the steam generated adjacent the hot wall 30 into the space at the left side of the vaporization section of vaporizer 25. Designated at 58 is a steam conduit connecting the left side portion of the vaporization section of vaporizer 25 to the turbine 11. Escape of exhaust steam from turbine 11 is provided through an exhaust conduit 59 arranged diametrically opposite the connection of conduit 58 to said turbine, as shown.

In operation, water is injected into the vaporizer 25 through the nozzle 55 and impinges on the hot wall 30, said wall 30 being heated to a very high temperature by the combustion of the liquid fuel in the right end portion of vaporizer 25. The steam vaporizes rapidly and flows back through the ports 57 into the space at the left end of the vaporizer 25 and thence flows through conduit 58 into the steam intake port of the turbine 11, driving the blades 13. The water pump 19 is driven by shaft 12 through the gears 16 and 17. The fuel pump 33 is likewise driven by shaft 26. The supply of fuel from the tank 31 is regulated in accordance with the temperature of the combustion chamber by the action of the thermostatic switch 50 which controls the electrical fuel valve 49.

Designated at 60 is an auxiliary vaporizer having an electrical heating coil 61 which is connected by a conductor 62, switch 41, conductor 43, voltage regulator 44 and conductor 45 to the ungrounded terminal 46 of the battery 47. The heating coil 61 is disposed on the right side of a transverse partition wall 63, viewed in the figure, and designated at 64 is a water supply nozzle positioned axially in the left end portion of the vaporizer 60 and connected by a conduit 65 through a manual valve 66 to the water supply conduit 54. A conical baffle 67 is provided in the vaporizer 60 similar to the baffle 56, said baffle 67 being provided with the steam return conduits 68 similar to the conduits 57. The water jet emerging from the nozzle 64 passes through the central aperture of the conical baffle 67 and impinges on the hot, transverse wall 63, at which point the water is vaporized and is transformed into high pressure steam. The steam returns through the left end portion of the vaporizer 60 through the ports 68 and is admitted to the turbine through a steam conduit 69.

If so desired, a suitable switch may be provided for selectively connecting the energizing conductor 62 for the heating coil 61 to the ungrounded terminal 46 of battery 47 or disconnecting conductor 62 from the battery, as desired, instead of operating the energizing winding 61 in parallel with the ignition coil 39.

Designated at 70 is a conventional starting motor whose shaft has mounted thereon a gear 71 which is contained in the housing of gear 15 and which is in mesh with gear 15, as shown. Also meshing with gear 15 is a gear 72 mounted on the shaft of a conventional generator 73 whose output terminal 74 is connected through a voltage regulator 75 to the ungrounded terminal 46 of battery 47, and which provides charging current for battery 47 while the turbine 11 is driven. The starting motor 70 is connected by a conductor 76, through a starting switch 77 on panel 42 and the conductor 78,

through the voltage regulator 44 and conductor 45 to the ungrounded terminal 46 of battery 47. It will be apparent that when switch 77 is closed, the starting motor 70 is then energized, causing gear 71 to drive gear 15 and shaft 12, which in turn drives the pump 19 through gears 16 and 17 and which also drives fuel pump 33 and causes fuel to be injected into the left end portion of vaporizer 25 through nozzle 35 for ignition thereof by spark plug 36. In the arrangement shown in the figure, the heating coil 61 is simultaneously energized and raises the wall 63 to a high temperature, whereby the water furnished in vaporizer 60 by nozzle 64 is vaporized and is returned through the steam supply conduit 69 to the turbine 11 in the form of high pressure steam. It will be therefore seen that in the arrangement specifically shown in the figure, the vaporizer 60 acts as a booster to facilitate quick starting of the turbine 11 and to provide high pressure steam for said turbine until the vaporization plate 30 of the main water vaporizer 25 has been brought to the required high temperature for full load operation.

While a specific embodiment of an improved steam generating apparatus has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A steam generating apparatus comprising a vaporization chamber, a heater adjacent said vaporization chamber and arranged to elevate at least one wall of the chamber to a high temperature substantially above the boiling point of water, a water reservoir, a pump connected to said reservoir, a supply conduit connected to said pump, a spray nozzle in said vaporization chamber connected to said supply conduit, a generally conical, centrally apertured partition wall secured in said vaporization chamber around said nozzle and located between said nozzle and said wall, said nozzle being directed through the aperture in the partition wall against the wall of the chamber, said partition wall having a plurality of steam escape ports therein to permit the passage of steam therethrough, and a steam outlet conduit connected to said chamber on the side of said partition wall opposite the first-named wall.

2. A steam generating apparatus comprising a vaporization chamber, a liquid fuel heater adjacent said vaporization chamber and arranged to elevate at least one wall of the chamber to a high temperature substantially above the boiling point of water, a water reservoir, a liquid fuel tank, a fuel supply conduit connecting said fuel tank to said heater, an electrically operated valve in said fuel supply conduit, a thermostatic switch mounted in said vaporization chamber and being responsive to the temperature of said chamber, means controlling connecting said switch to said valve for closing said valve at a predetermined temperature, a pump connected to said reservoir, a supply conduit connected to said pump, a nozzle in said vaporization chamber connected to said supply conduit, said nozzle being directed against said wall of the chamber, a generally conical, centrally apertured partition wall secured in said vaporization chamber around said nozzle and located between said nozzle and said first-named wall,

said nozzle being aligned with the aperture in said partition wall, whereby to direct a stream of water through said aperture, and a steam outlet conduit connected to said chamber on the side of said partition wall opposite said first-named wall, said partition wall having ports therein to permit the passage of steam formed when the stream of water impinges against said first-named wall of the chamber.

3. A steam generating apparatus comprising a generally cylindrical vaporization chamber, a heater adjacent said vaporization chamber and arranged to elevate an end wall of the chamber to a high temperature substantially above the boiling point of water, a water spray nozzle in said vaporization chamber, a generally conical, centrally apertured partition wall secured in said vaporization chamber around said nozzle and located between said nozzle and said first-named wall, said partition wall having a plurality of steam escape ports therein to permit the passage of steam formed by the impinge-

ment of water on said first-named wall of the chamber, and a steam outlet conduit connected to said chamber at a portion thereof remote from said first-named wall.
